UNITED STATES PATENT OFFICE.

FREDERICK GRINNELL, OF PROVIDENCE, RHODE ISLAND.

AUTOMATIC FIRE-EXTINGUISHER.

SPECIFICATION forming part of Letters Patent No. 231,712, dated August 31, 1880.

Application filed May 31, 1880. (No model.)

To all whom it may concern:

Be it known that I, FREDERICK GRINNELL, of the city and county of Providence, and State of Rhode Island, have invented a new 5 and useful Improvement in Automatic Fire-Extinguishers, (Case C;) and I hereby declare that the following is a full, clear, and exact description of the same, reference being had to the accompanying drawings, forming part of 10 this specification.

This invention consists in certain details of construction and combinations of parts in an automatic fire-extinguisher, as will herein-after be described, and pointed out in the 15 claims.

Figure 1 is a perspective view of the interior of a building provided with a system of pipes arranged to distribute water for the purpose of extinguishing accidental fires, and 20 also a system of wires or cords connected at intervals with links secured by a solder fusible at a low temperature, arranged to release the valve by which the water-supply to the pipes is governed. Fig. 2 is a sectional view 25 of the valve governing the water-supply to the pipes.

In the drawings, A represents a valve connected with the water-main and with the stand-pipe B, to which the branch pipes C C are connected. The branch pipes C C are provided 30 with rose-head or other distributors, or the pipes may be perforated so as to form distributors.

d d represent a system of cords or wires 35 passing through the various parts of a building or a section of the same and connected with the weight D.

e e are links made of fusible material or united by means of fusible solder, so that when 40 the temperature of any portion of the building is raised above the normal condition sufficient to indicate a fire the links will separate, or the wires or cords will part and release the weight D.

45 The valve A consists of the case a, provided with the branches b and c, c being the water-inlet, and b the outlet.

f is a piston, the face of which is provided 50 with a flexible or elastic cup, so constructed that the pressure of the water will force it

against the sides of the cylinder a and make a water-tight joint. The axial length of the piston should be as great or greater than the diameter of the outlet-opening, so that the water cannot pass around the piston.

A stuffing-box may be used where the piston-rod passes through the case a; but I prefer to use the same without a stuffing-box, so as not to impede the motion of the piston when the same is released.

The piston-rod is supplied with one or two nuts, h h, and the stop i is arranged to hold the piston in the desired position as long as the weight D is suspended by the wires or cords d d. This may be accomplished in various ways, two of which are shown in the drawings, viz: The stop i may form part of a bell-crank pivoted at k, the weight being secured to the other end of the bell-crank, and to assist in the opening of the valve the upper 65 portion of the arm i may be curved, so as to force the piston outward by the descent of the weight D; or the stop i may extend from an arm hinged at l, the weight being secured to the free end, so that as soon as the cords or 70 wires d d are severed the descent of the weight 75 will withdraw the stop and the pressure on the piston will move the same beyond the discharge-opening.

To prevent water from entering the system 80 of pipes and allow any water that by any means may pass the piston or remain in the pipes to be automatically discharged, I provide the case a with the drip-opening m, into 85 which a pipe or a draw-off cock may be secured. This opening m will be covered by the piston f and packing g when the water-supply is open, and any loss or diminution of pressure is thereby avoided. The piston may be released in any other manner, by electricity 90 or other means arranged to release the piston or remove the stop, so that the pressure will open the supply.

I am aware that the water-supply to fire-extinguishers has heretofore been controlled by 95 means of a valve; but such valves either allowed a portion of the water to pass by the valve, or when they were made tight the valve was forced against a fixed seat, and any sudden excess of pressure was liable to cause a 100

leak of water, or the valve had to be opened against the water-pressure, thus requiring considerable force.

Having thus described my invention, I claim
5 as new and desire to secure by Letters Patent—

1. The combination, with a supply-pipe, a series of distributing-pipes communicating therewith, a cord or wire extending through
10 the apartments in which the distributing-pipes are located and united in each of said apartments by fusible solder, and a weight upheld by said cord or wire, of a cylinder provided
15 with inlet and outlet openings, a piston-valve provided with elastic packing located in said

cylinder, and a stop-lever, one end of which engages the valve-stem and retains the valve in a closed position, and the outer end thereof connected with the weight, which is upheld by the cord or wire, substantially as set forth.

2. The combination, with a system of distributing-pipes, of a piston interposed between the water-supply and the distributors, and a drip-outlet arranged to carry off any water in the pipes, as described.

FREDERICK GRINNELL.
